UNITED STATES PATENT OFFICE

149,590

DESIGN FOR A LETTER OPENER OR SIMILAR ARTICLE

Hans K. W. Schlegel, Chicago, Ill.

Application April 16, 1947, Serial No. 138,429

Term of patent 14 years

(Cl. D74—1)

To all whom it may concern:

Be it known that I, Hans K. W. Schlegel, a citizen of the United States, residing at Chicago, in the county of Cook and State of Illinois, have invented a new, original, and ornamental Design for a Letter Opener or Similar Article, of which the following is a specification, reference being had to the accompanying drawings, forming a part thereof.

Fig. 1 is a side elevational view of a letter opener, showing my new design, the opposite side presenting substantially the same appearance as the side shown; and

Fig. 2 is an edge elevational view thereof.

I claim:

The ornamental design for a letter opener or similar article, as shown and described.

HANS K. W. SCHLEGEL.
